UNITED STATES PATENT OFFICE.

OVE L. GAMMELGAARD, OF ATTLEBORO, MASSACHUSETTS, ASSIGNOR TO ELECTRIC CHAIN COMPANY, OF ATTLEBORO, MASSACHUSETTS, A CORPORATION OF MAINE.

BRACELET.

1,059,536.

Specification of Letters Patent.

Patented Apr. 22, 1913.

Application filed January 2, 1913. Serial No. 739,591.

To all whom it may concern:

Be it known that I, OVE L. GAMMELGAARD, a citizen of the United States, residing at Attleboro, in the county of Bristol 5 and State of Massachusetts, have invented certain new and useful Improvements in Bracelets, of which the following is a specification.

My invention relates to bracelets of the 10 lazy tongs type and is designed especially as an improvement of the structure set forth in my prior United States Patent No. 836,109 dated November 20, 1906.

The essential objects of my invention are 15 to strengthen the connection of the setting member with the cross arms of the bracelet band so as to avoid the use of solder, or the necessity of riveting or swaging the connecting member to the shell of the setting 20 member whereby the shell is defaced and the union insecure; also to avoid the non-uniformity in appearance and action of an arm adjacent the setting members of half the length of the cross arms of the bracelet 25 band; and to simplify and render less expensive the detailed construction of the setting member and its connection with the bracelet band.

To the above ends essentially my invention 30 consists in such parts and combinations of parts as fall within the scope of the appended claims.

In the accompanying drawings which form a part of this specification:—Figure 1 35 is a front elevation of my novel bracelet in contracted or normal position, Fig. 2, a rear elevation of a section of the bracelet including the setting member, showing the parts expanded, Fig. 3, a section on line $\alpha\alpha$ of Fig. 2, Figs. 4 and 5, plan and side elevations respectively of the guard plate, Figs. 6 and 7, side and bottom plan elevations respectively of the shell of the setting member, Fig. 8, a plan of the base plate of base member, Figs. 9 and 10, side and front elevations respectively of the front ornamental shells of the extension plates, Figs. 11 and 12, similar elevations respectively of the back ornamental shells of the extension plates, and Figs. 13 and 14, sections 45 respectively on lines $y\gamma$ and $z\zeta$ of Fig. 2.

Like reference characters indicate like parts throughout the views.

A represents the band or body of my 55 bracelet which may be of any usual form of

lazy tongs construction comprising the front series of arms a and the back series of arms b , the individual arms of both series being centrally pivoted to each other. A setting or ornamental member C is provided, comprising a cylindrical wall c provided with upper and lower inturned flanges c' and c'' respectively. Extending through the flange c'' and upwardly some distance in the wall c are pairs of slots c^3 at diametrically opposite 60 points. An ornament or ornamental cup plate D is embraced by the flange c' and has a lateral flange d resting against the inner face of the latter. The flange or rolled over portion c^2 supports a back plate E 65 which has pairs of diametrically oppositely disposed lugs e registering in the slots c^3 . Intermediate the members D and E is located a guard plate F shown in detail in Figs. 4 and 5. This plate is formed of thin 70 metal and has a tapering body f whose retracted or front end abuts against the back of the ornament or plate D forcing the latter into tight contact with its seat in the flange c' . The rear or base portion of the member 75 F rests upon the plate E and is provided with diametrically oppositely disposed integral arms f^2 , integral with two arcuate extension plates f^3 . The arms f^2 pass through the slots c^3 . The opposite margins 80 of the portions f^3 are provided with perforations f^4 to receive hollow pivot members f^5 as best seen in Fig. 5. To the front of each plate f^3 are swaged ornamental hollow curved shells g provided with marginal 85 slots g' to admit the arms f^2 , also with elevations g^2 at one end to allow clearance of the pivots or rivets. The edges of the shells are rolled over as at g^3 to clamp against the rear of the member f^3 ornamental plates h . 90 The latter are shorter than the plates g so as not to interfere with one pivot, and have elevations h' at their ends to allow clearance of the second pivot.

The rivets f^5 pivotally engage the ends of 100 the adjacent pair of cross arms a and b . In detail the arm a comprises the hollow outer shell i which engages by a rolled over portion i^2 a flat back plate j provided with end perforations k to receive the headed 105 over rivets. The arm b has an outer hollow shell l which holds by a bead l^2 an inner plate m provided with end perforations n to receive the headed pivots or rivets. One of the pivots f^5 is that in the plate f^3 , while 110

the opposite end pivots *o* are the usual arm pivots.

What I claim is:—

1. The combination with the crossed arms 5 of a lazy-tongs bracelet, of a setting member comprising a shell provided with oppositely disposed openings, an ornamental member engaging the front of the shell, a base plate in the rear of the shell and engaged thereby, a guard plate within the shell 10 pressing against the ornamental member, and engaged by the base plate, arms integral with the guard plate extending through the openings in the shell, extension plates 15 integral with the arms exterior of the shell, and means for pivotally connecting the ends of the extension plates with the ends of the crossed arms.

2. The combination with the crossed arms 20 of a lazy-tongs bracelet, of a shell provided with diametrically opposite openings in its side, inturned flanges upon the front portion of the shell, an ornamental member mounted within the flange and engaging the 25 inner face of said flange, a conical guard plate in the shell having its retracted portion in contact with the inner face of the ornamental member and engaged by the shell and held thereby, arms integral with 30 the guard plate extending through the openings, extension plates upon the arms, and pivots in the ends of the extension plates engaging the ends of the crossed arms.

3. The combination with the crossed arms 35 of a lazy-tongs bracelet, of a shell provided with openings in its side, a flange upon the front portion of the shell, an ornamental member mounted in the front of the shell and having a portion of its margin resting 40 against the inner face of the flange, a guard plate having one end abutting against the back of the ornamental member, arms upon the guard plate extending through the openings, a flange upon the rear of the shell, a 45 base plate in the shell between the guard plate and the last mentioned flange, exten-

sion plates integral with the arms, and pivot members connecting the ends of the extension plates with the ends of the crossed arms.

4. The combination with the crossed arms 50 of a lazy-tongs bracelet, of a shell provided with four openings in its side, two of the openings being diametrically opposite of the two other openings, an inturned flange integral with the forward portion of the shell, an ornamental member mounted in the shell engaging the flange, an inclined guard member abutting against the ornamental member located within the shell, arms integral with the 60 guard member extending through the openings, a base plate mounted in the back of the shell and engaged thereby, lugs upon the base plate also entering said openings, extension plates integral with the arms, and pivot members in the ends of the extension plates engaging the ends of the crossed arms. 65

5. The combination with the crossed arms 70 of a lazy-tongs bracelet, of a shell provided with openings in its side, a flange integral 75 with the front of the shell, an ornamental member engaged by the flange, a guard member in the shell abutting against the ornamental member, arms integral with the guard plate extending through the openings, a base plate mounted in the rear of the shell and engaged thereby, extension plates upon the ends of the arms and provided with perforations in their ends, rivets extending 80 through the perforations and loosely engaging the ends of the crossed arms, ornamental plates upon the front faces of the extension plates provided with elevated portions above the rivets, and ornamental plates upon the back faces of the extension plates provided 85 with elevations above the rivets.

In testimony whereof I have affixed my signature in presence of two witnesses.

OVE L. GAMMELGAARD.
